CLAIM

The ornamental design for an airplane seating unit, as shown and described.

DESCRIPTION

FIG. 1 is a top view of an airplane seating unit, illustrated in a dining mode;

FIG. 2 is a side view of the airplane seating unit shown in FIG. 1;

FIG. 3 is a perspective view of the airplane seating unit shown in FIG. 1;

FIG. 4 is a top view of the airplane seating unit shown in FIG. 1, illustrated in a bed mode;

FIG. 5 is a side view of the airplane seating unit shown in FIG. 4;

FIG. 6 is a perspective view of the airplane seating unit shown in FIG. 4;

FIG. 7 is a top view of the airplane seating unit shown in FIG. 1, illustrated in a lounge mode;

FIG. 8 is a side view of the airplane seating unit shown in FIG. 7; and,

FIG. 9 is a perspective view of the airplane seating unit shown in FIG. 7.

The broken lines are for illustration only and form no part of the claimed design.

1 Claim, 9 Drawing Sheets
